UNITED STATES PATENT OFFICE.

HOWARD M. NICHOLS, OF SWARTHMORE, PENNSYLVANIA, ASSIGNOR TO THE ATLANTIC REFINING COMPANY, OF PHILADELPHIA, PENNSYLVANIA, A CORPORATION OF PENNSYLVANIA.

BARREL-MAKING APPARATUS.

Application filed June 25, 1921. Serial No. 480,293.

To all whom it may concern:

Be it known that I, HOWARD M. NICHOLS, a citizen of the United States, residing at Swarthmore, county of Delaware, State of Pennsylvania, have invented a new and useful Barrel-Making Apparatus, of which the following is a specification.

My invention relates to barrel making machinery, and particularly to apparatus whereby the assembled barrel staves may be chamfered, trimmed, howeled and crozed.

In accordance with my invention, barrels of various or different lengths may be chamfered, trimmed, howeled and crozed in one operation.

Further in accordance with my invention, barrels of various or different diameters formed of old or new staves, or in part of old and in part of new staves, may be chamfered, trimmed, howeled and crozed in one operation.

By employment of apparatus embodying my invention, less material is spoiled, the quality of the work is greatly improved, and there is saved a large part of the cost of labor involved in chamfering, trimming, howeling and crozing by hand.

My invention resides in the apparatus and features of construction hereinafter described and claimed.

For an illustration of one of the various forms my invention may take, reference is to be had to the accompanying drawings, in which:

Fig. 1 is a fragmentary sectional view illustrating the operations performed upon the barrel staves.

Fig. 2 is a side elevational view of apparatus embodying my invention.

Fig. 3 is an end elevational view of the apparatus shown in Fig. 2.

Fig. 4 is a fragmentary plan view illustrating the trimming knife structure.

Fig. 5 is a fragmentary view, partly in section, illustrating parts of my apparatus.

Fig. 6 is a fragmentary side elevational view of the safety cap and associated parts.

Fig. 7 is an end elevational view of the structure shown in Fig. 6.

Fig. 8 is a fragmentary side elevational view of the barrel rotating structure.

Fig. 9 is an end elevational view of the structure shown in Fig. 8.

Fig. 10 is a side elevational view of the rocking frame and associated parts. 55

Fig. 11 is an end elevational view of the same.

Fig. 12 is an end elevational view showing a shaft drive.

Fig. 13 is a side elevation of the barrel 60 cradle and associated parts.

Fig. 14 is an end elevational view of the same.

Fig. 15 is a side elevational view of parts shown in Fig. 13. 65

Referring to Fig. 1, there is shown in section the end of a barrel stave *s* which has been subjected to the operations performed by my hereinafter described apparatus. The trim is indicated at *a*, the chamfer at *b*, the croze at *c* and the howel at *d*, these being the cuts well understood in the art as performed upon the staves of a barrel whose head is introduced into the howel and croze and therein snugly held by a hoop 70 or hoops driven longitudinally of the barrel staves, as from the left toward the right, Fig. 1.

Referring to Figs. 2 and 3, *F* is any suitable frame supporting or carrying various 80 parts of my apparatus.

Journalled in the frame *F* is the shaft *S* upon one end of which is secured the rotary cutter head or crozer head *C* carrying, as well understood in the art, the chamfer, 85 howel and crozing cutters or knives.

Pivoted to the frame *F* at 1 is the rocking frame *R* connected by link bar 2 with the lever 3 pivoted at 4 and carrying at its opposite end the counterweights 5. To the 90 lever 3 is attached the foot treadle 6 by which the lever 3 and attached parts are actuated, the downward or counterclockwise rotation of the rocking frame *R*, as viewed in Fig. 3, being limited by the adjustable set screw 7 carried by the frame *F*. The rocking frame *R* is provided at its one side with the circular or other suitable opening 9 for receiving the end of a barrel *B*, the latter indicated in dotted lines in 100 Fig. 2, in full lines in Figs. 13 and 14, and in fragmentary section in Fig. 5. Depending from the rocking frame *R* are the bracket members 10 and 11, to which are pivoted, respectively, at 12 and 13 the barrel guides 14 and 15, the latter having the 105

two barrel-engaging portions 16 and 17. The member 14 partakes of limited movement upon its pivot 12, the extent of movement being limited by the slot 18 in the member 14 through which extends the fixed bolt 19. Similarly, the member 15 partakes of movement upon its pivot 13, the extent of the movement being limited by the slot 20 through which extends the fixed bolt 21.

10 The guide members 14 and 15 form, therefore, a three-point suspension or engagement for the inside of the barrel B adjacent that end thereof presented to the cutter C, and upon these yielding guide members the barrel is supported while subjected to the cutting operations and simultaneously rotated by the toothed wheel T engaging the barrel B on its periphery.

15 The shaft S is driven by any suitable means, as by a pulley or equivalent, not shown. The toothed barrel-rotating wheel T is driven by the shaft S through any suitable means. In the example illustrated, there is secured upon the shaft S a pulley 22, Fig. 12, which drives the belt 23, which in turn drives the pulley 24 secured upon the idler shaft 25, which in turn drives the pulley 26 which drives the belt 27 which in turn drives the pulley 28 secured upon the shaft S¹, upon which is secured a gear 29 meshing with and driving the gear 30 secured upon the shaft S² upon which is secured the aforesaid barrel-rotating wheel T. The shafts S and S¹ are carried by the frame F, the shaft S¹ and the pivot 1 for the rocking frame R being co-axial or identical. The shaft S² is carried by the bracket 31 pivoted upon the shaft S¹, and to the bracket 31 is secured the hand lever 32 by which the shaft S² and the wheel T driven thereby may be rotated about the shaft S¹ as a center to bring the toothed wheel T into engagement with the exterior of the end of the barrel. The lever 32 carries a counter-weight 33, as indicated in Figs. 2, 3, 8 and 9, which counterweight withdraws the wheel T from operative driving relation with respect to the barrel into the shield 34 when the hand lever 32 is released.

20 Referring to Figs. 2, 3, 6 and 7, K is a safety cap for enclosing the cutter head C when not engaged with a barrel, the cap K preventing contact with the rotating cutter head by the hands or person of the operator.

25 The cap K is open at its left end, Figs. 2 and 6, to pass over the cutter head C, and is closed at its opposite end. The cap K is secured to a member 35 pivoted at 36 to a bracket 37 secured upon the frame F. Pivoted at 38 to the bracket 10 carried by the rocking frame R, and therefore movable therewith is the downwardly extending rod 39 extending through a hole in the lever 40 pivoted at 41 to the bracket 42 secured to the frame F. Carried by the rod 39 on op-

posite sides of the end of the lever 40 are the springs 43 and 44, between which the lever 40 is yieldingly held. At the opposite end of the lever 40 is hung the counter-weight 45. Pivoted to the lever 40 at 46 is a rod 47, pivoted at 48 to the bell crank 49 pivoted at 50 to the bracket 51 secured to the frame F. Pivoted to the bell crank 49 at 52 is a rod 53 pivoted to the member 35 at 54.

70 The closed end of the safety cap K is provided with a door or flap 55 hinged to the cap at 56 and preferably carrying a weight 57 which biases it to vertical position, whereby when the cap is in position covering the cutter C, as indicated in Fig. 80 6, the door or flap 55 is closed, whereas when the cap K is in the position indicated in Figs. 2 and 3, when the cutter is in operation and the cap removed therefrom, the flap or door opens, allowing any accumulated 85 chips or shavings to drop out.

80 Referring to Figs. 2, 13, 14 and 15, A is a cradle for receiving and holding the barrel B, which upon delivery to the cradle from right toward the left, as viewed in Figs. 2 and 13, rolls upon the idler rollers 58 and 59 pivoted upon the cradle A. When the barrel is in the position indicated in Fig. 2 and is rotated by the toothed wheel T, it rolls upon the idler rollers 60 and 61 pivoted 95 upon the cradle A.

90 The cradle A has downwardly extending lugs 62 and 63 by which it is pivoted upon the shaft 64 carried by the standards 65 resting upon the floor or other support and connected by braces 66 with the frame F. The cradle is capable of sliding movement longitudinally of the shaft 64 between the collars or stops 67, which sliding movement, in addition to the rocking movement of the cradle upon the shaft 64, permits a barrel, notwithstanding variations in diameter or other dimensions, being properly and suitably located with respect to the cutter head C and associated mechanism. Secured to the 100 cradle A at its left end, Figs. 2 and 13, is the bar 68 which at its other end is suitably attached to the foot-operated lever 3.

105 Referring to Figs. 4 and 5, there are carried by the frame F vertical pins 69, 69, extending through diagonal slots 70, 70 in a block or member 71 carrying the trimmer knife 72, whose cutting edge or end may be advanced toward the end of a barrel or removed therefrom by the operating lever 73 pivoted at 74 to a fixed bracket 75 and pivoted at 76 to the rod 77 pivoted at 78 to the block 71. By advancing the knife into engagement with the end of the rotating barrel, the end of the barrel is trimmed to correspond, for example, to the trim a of Fig. 1.

115 The operation is as follows:

120 The barrel staves, which may be staves from old barrels, or new staves, or both new and old staves, are assembled with the 130

125

usual temporary truss hoops on the outside, so forming a barrel without heads. The operator places the barrel upon the cradle A, which may rock upon the pivot 64 and which may slide sidewise, longitudinally of that shaft. The cradle makes it possible properly to locate barrels of different diameters or sizes with respect to the crozer head or cutter head C. With the barrel upon the cradle, its end is passed over the safety cap K, which at this time is in the position indicated in Fig. 6, that is, covering the crozer head C; the barrel in this position rests upon the yielding guides 14 and 15 with which the inside of the barrel end contacts. The shaft S carrying the crozer head C is now set in motion, unless it has been left running after operating upon the preceding barrel. The operator then actuates the main control lever 3, as by foot treadle 6, or any other suitable means, tilting the lever 3 upon pivot 4 in opposition to the counterweight 5, in counterclockwise direction, as viewed in Figs. 3, 10 and 14. Such movement of the lever 3 causes counterclockwise movement of the rocking frame R about its pivotal center 1, as viewed in Figs. 3, 7 and 10, through the downward pull exerted by the rod 2. This movement of the rocking frame R carries the bracket 10 downwardly, thereby operating the safety cap K, through rod 39 and the parts intervening between the same and the bracket 35, to inclined position indicated in Fig. 2, uncovering the crozer head or cutter head C. The guides 14 and 15 upon which the inside of the barrel is resting are similarly lowered by the aforesaid movement of the rocking frame R, bringing the inside of the end of the barrel into proper relation with the cutter head C, the extent of descent of the frame R being limited by the adjusting screw 7, which determines the depth of cut by the knives on the crozer or cutter head C. The operator now pulls downwardly upon the hand lever 32, bringing the rotating toothed wheel T into engagement with the outside of the barrel, causing it to rotate while the crozer or cutter head C is rotating at high speed, whereby the chamfer, howel and croze are cut circumferentially inside the barrel at its end. When the barrel has made at least one complete revolution in contact with the knives of the cutter head, the lever 32 is released and the counterweight 33 withdraws the wheel T from the barrel. The shaft S may then be stopped, or if desired, may be allowed to continue to rotate until the next barrel is operated upon.

By actuating the lever 73, the trimmer knife 72 is brought into engagement with the end of the rotating barrel to trim the end thereof. This trimming action may be performed before, after or during the operation of cutting the croze, howel and chamfer.

Upon release of the lever 3, as by removal of the foot of the operator from the treadle 6, the counterweight 5 restores it to its normal position, causing the rocking frame R to return to its normal position and the cap K to return to its position covering or closing the cutter head C. The barrel is then turned end for end, and the same operation is performed upon its other end.

By apparatus of the character above described, barrels of various or different lengths may be chamfered, trimmed, howeled and crozed in one operation. Furthermore, barrels of various or different diameters made up of old staves, or new staves, or both, may be chamfered, trimmed, howeled and crozed in one operation. The labor cost involved in chamfering, trimming, howeling and crozing barrels by hand, particularly when made from old, that is, previously used staves, is very greatly reduced by recourse to my apparatus, in some cases at least 60 per cent of the cost of hand operation being eliminated. Furthermore, less material is spoiled and the quality and uniformity of the work are greatly improved.

What I claim is:

1. Barrel making apparatus comprising a rotatable cutter head, a frame upon which the inner side of one end of a barrel may rest, means for supporting the other end of the barrel, and means for moving said frame radially of the cutter head to tilt the first mentioned end of the barrel toward and from said head.

2. Barrel making apparatus comprising a cutter head, a frame upon which the inner side of one end of a barrel may rest, means for supporting the other end of the barrel, means for moving said frame to tilt the first mentioned end of the barrel toward and from said cutter head, and means for rotating the barrel about its longitudinal axis, the said rotating means serving also to hold the barrel in position upon the said supporting means.

3. Barrel making apparatus comprising a cutter head, a frame movable with respect thereto, and guide members loosely mounted upon said frame upon fixed points of support, to form a plurality of equalized points of support for the inside of the end of a barrel.

4. Barrel making apparatus comprising a cutter head, a frame movable with respect thereto, guide members loosely mounted upon said frame upon fixed points of support, to form a plurality of equalized points of support for the inside of the end of a barrel, and means for rotating said barrel upon said guide members with respect to said cutter head.

5. Barrel making apparatus comprising a cutter head, movable means for supporting a barrel and for bringing its one end into

- operative relation to said cutter head, a relatively stationary support for the other end of the barrel, means for rotating said barrel comprising a rotary member engaging the exterior of the barrel, and means for moving said rotary member to and from engagement with said barrel. 5
6. Barrel making apparatus comprising a cutter head, movable means for supporting a barrel and bringing its one end into operative relation to said cutter head, a relatively stationary support for the other end of the barrel, means for rotating said barrel with respect to said cutter head comprising a rotary toothed wheel adapted to engage the exterior of the barrel, and means for moving said wheel to and from engagement with the barrel. 10
7. Barrel making apparatus comprising a cutter head, a frame for supporting one end of a barrel in operative relation to said cutter head, means for moving said frame to tilt the barrel with respect to said cutter head, and adjustable means predetermining the extent of movement of the barrel toward said cutter head. 20
8. Barrel making apparatus comprising a cutter head, a cradle for receiving a barrel, and means for pivoting said cradle for moving the barrel end with respect to said cutter head. 30
9. Barrel making apparatus comprising a cutter head, a movable frame for engaging one end of a barrel to position said end radially of the cutter head, and a cradle for receiving the barrel, the said cradle being slidably supported to permit movement thereof in a plane transverse to the path of movement of said frame. 35
10. Barrel making apparatus comprising a cutter head, a cradle for receiving a barrel, a pivotal support for said cradle, and means allowing transverse movement of said cradle. 40
11. Barrel making apparatus comprising a cutter head, a control lever, a rocking frame for supporting a barrel end movable by said lever, a pivoted cradle for holding the barrel, and a connection from said cradle to said lever. 45
12. Barrel making apparatus comprising a cutter head, a frame, means on the frame adapted to engage the inner side of one end of a barrel and of such structure that they automatically conform themselves to the curvature of barrels of various diameters, and means for moving the said support to tilt one end of the barrel toward and from the said cutter head. 55
13. Barrel making apparatus comprising a cutter head, a pivoted frame, guides carried by said frame and upon which the inside of the end of a barrel is adapted to rest, means for rocking said frame with respect to said cutter head, a rotary member adapt- 60
- ed to engage the outside of the barrel to rotate the same, and an arm supporting said rotary member and pivoted concentrically with said frame and movable independently of said frame toward and away from the barrel. 70
14. Barrel making apparatus comprising a cutter head, a frame, means on the frame adapted to engage a barrel and of such structure that they automatically conform themselves to the curvature of barrels of various diameters, and means for moving the said frame to move one end of the barrel toward and from the said cutter head. 75
15. Barrel making apparatus comprising a cutter head, a frame movable with respect thereto, guide structure carried by said frame and upon which the inside of the end of a barrel is adapted to rest, and means engaging the barrel exteriorly thereof for effecting its rotation. 80
16. Barrel making apparatus comprising a cutter head, a frame movable with respect thereto, guide members carried by said frame and upon which the inside of the end of a barrel is adapted to rest, and means for imparting relative rotating movement to the barrel and the said cutter head, the said means serving also to hold the barrel in engagement with the said guide members. 90
17. Barrel making apparatus comprising a cutter head, a movable frame, guide members on said frame for supporting a barrel with its end in operative relation to said cutter head, and a rotatable member for rotating the barrel and holding it in engagement with the said guide members. 100
18. Barrel making apparatus comprising a cutter head rotatable about a fixed axis, a guide member adapted to be engaged by the inside of the end of a barrel and movable radially of the cutter, and an actuating member for engaging the exterior of the barrel to rotate the same and to hold it in engagement with the said guide member. 105
19. Barrel making apparatus comprising a cradle for supporting one end of a barrel and tilttable on a horizontal axis disposed transversely of the barrel, a cutter head, guide members for supporting the other end of said barrel, means for holding the barrel in engagement with said guide members, and means for moving said guide members in a direction radial to the barrel to vary the position of the barrel with respect to the cutter head. 115
20. Barrel making apparatus comprising a cradle for supporting one end of a barrel and tilttable on a horizontal axis disposed transversely of the barrel, a cutter head, guide members for supporting the other end of said barrel, and located adjacent to said cutter head, rotating means for holding the barrel in engagement with said guide members, and means for moving said guide mem- 120
- bers, and means for moving said guide mem- 125
- bers, and means for moving said guide mem- 130

bers in a direction radial to the barrel, the said guide members and the barrel rotating means being respectively disposed interiorly and exteriorly of the said other end of the 5 barrel.

21. Barrel making apparatus comprising a cutter head, and a cradle for supporting a barrel with one end thereof adjacent to the cutter head, the cradle being mounted upon 10 a horizontal pivot disposed transversely of the barrel and having free pivotal movement.

22. Barrel making apparatus comprising a rotatable cutter head mounted upon a fixed 15 axis, and a cradle for supporting a barrel with one end thereof adjacent to the cutter head, the cradle being mounted upon a horizontal pivot disposed transversely of the barrel and having free pivotal movement.

23. Barrel making apparatus comprising a cutter head, a rocking frame for supporting a barrel for movement to operative position with respect to said cutter head, barrel-rotating means carried by said frame, a 25 control lever for the said frame, and a lever for controlling the operation of the said barrel-rotating means.

24. Barrel making apparatus comprising a cutter head, a rocking frame for supporting 30 a barrel for movement to operative position with respect to said cutter head, barrel-rotating means carried by said frame, a control lever for the said frame, and a lever for controlling the operation of the said 35 barrel-rotating means, the said levers being independently operable.

25. Barrel making apparatus comprising a cutter head, a rocking frame for supporting 40 a barrel for movement to operative position with respect to said cutter head, barrel-rotating means carried by said frame, a

control lever for the said frame, a lever for controlling the operation of the said barrel-rotating means, and counterweights for normally holding said levers in retracted position. 45

26. Barrel making apparatus comprising a cutter head, a frame upon which the inner side of one end of a barrel may rest, means for supporting the other end of the barrel, 50 means for moving said frame to tilt the first mentioned end of the barrel toward and from said cutter head, and means for rotating the barrel about its longitudinal axis.

27. A barrel crozing machine comprising 55 a fixed rotating crozing cutter, and a support movable in the cutting plane of the cutter toward and from the same, adapted to engage the inner upper side of one end of the barrel adjacent the cutter and to support this end in proper relation to the cutter, and the form and dimensions of which both circumferentially and axially of the barrel are such as to permit one end of the barrel to be tilted down upon or away from 60 65 said support and to move therewith toward and from the cutter.

28. Barrel making apparatus comprising a cutter, a frame, guide members mounted on the frame in position to be engaged by 70 the end of a barrel and spaced circumferentially with respect to the barrel, and means for moving said frame to carry the barrel toward and from said cutter, the said guide members being loosely mounted to permit 75 them to assume positions in conformity with barrels of various curvatures.

In testimony whereof I have hereunto affixed my signature this 23rd day of June, 1921.

HOWARD M. NICHOLS.
